REVERSIBLE TWO-WAY TUMBLE PLOW

Robert A. Walker and Earl V. Walker,
Lingle, Wyo.

Application March 9, 1951, Serial No. 214,718

7 Claims. (Cl. 97—25)

1

This invention relates to an improved construction of two-way reversible tumble plow and more particularly to an automatic means for controlling the reversing of the plow whereby manual operations are eliminated together with the possibility of incorrect manual operation.

More particularly, it is an aim of the present invention to provide an improved construction of plow embodying novel automatic features for use with a tumble plow of the type as shown in U. S. Patent 1,915,866 wherein a possibility of the plow being inadvertently unlatched to tumble when the frame is unlatched and lowered from an elevated, transport position is eliminated.

Another object of the invention is to provide an improved means to automatically adjust the center line of the draft which is accomplished without any manual operation automatically as the tumbling of the plow beam is completed which in addition to eliminating a manual operation also enables the plow to be turned more slowly and less sharply at the end of a field.

A further object of the invention is to provide automatic means to positively prevent the unlatching of a wheel in a fully lowered position as sometimes occurs with a manually actuated latch as now employed with tumble plows when the furrow engaging wheel is released before the plow has reached a furrow into which the wheel is to drop and which is necessary in order that plows may assume a sub-soil, furrow forming position at the end of the field.

Various other objects and advantages of the invention will hereinafter become more fully apparent from the following description of the drawings, illustrating a presently preferred embodiment thereof, and wherein:

Figure 1 is a side elevational view showing a plow embodying the invention in a working position and disposed for throwing the earth to the left or toward the far side of the plow;

Figure 2 is a top plan view of the plow with certain of the parts omitted for clarity;

Figure 3 is an enlarged fragmentary side elevational view partly in vertical section showing the parts as illustrated in Figure 1 prior to unlatching the frame from an elevated, transport position for permitting the frame to assume its position of Figures 1 and 2;

Figure 4 is an enlarged longitudinal substantially central sectional view of a portion of the plow, on an enlarged scale and taken substantially along a plane as indicated by the line 4—4 of Figure 2, and

Figure 5 is a fragmentary perspective view

of a portion of the plow illustrating the improved construction of latch releasing means.

Referring more specifically to the drawings, as most of the structure of the plow, designated generally 9 and comprising the invention is identical or substantially identical with the plow as disclosed in Patent 1,915,866, reference is made to said patent for a detailed disclosure of such parts which will be described herein only in reference to the extent that said parts are modified in their construction or operation by the improvements embodied in the present invention. Further, for the purpose of simplicity the parts as disclosed in the plow 9 will be referred to by reference numerals corresponding to the identical parts in Patent 1,915,866.

Said identical or substantially identical parts include a draft bar 14 which is pivoted on a pin 15 intermediate of its ends and which pin 20 connects the draft bar to the plow frame at its forward end. The frame is formed by the side bars 10 and 11 which are suitably braced intermediate of their ends and which are provided with inwardly offset rear ends 19 and 20, respectively, which are connected by a transverse shaft 21. A beam structure, designated generally 30 is journaled intermediate of its ends on the shaft 21 for rotation about said shaft as a horizontal axis and includes corresponding cross members 34 and 35 defining the end portions of the beam structure. The beam structure 30 has a pair of right-hand plow bodies 36 and 52 projecting from one side of the plane thereof and a pair of left-hand plow bodies 38 and 50 projecting from the opposite side of the plane thereof, one of which pairs of plow bodies are disposed above the beam structure when the other pair of plow bodies are in an operative position, as illustrated in Figure 1.

The plow includes the two transversely aligned left and right ground wheels 70 and 71 journaled on the ends of axles 72 and 73, respectively, said axles having vertical portions slidably and turnably mounted in sleeves 75 of brackets 74 which are secured to the frame sides 10 and 11. Each frame side is yieldably supported relatively to the adjacent axle by a contractile spring 76 which is secured at its lower end to the frame and at its upper end to a sleeve or collar 77 which is slidably and turnably mounted on the reduced upper end of the axle 72 or 73.

The wheels and axles are vertically adjusted relatively to the plow frame 10, 11 by levers 80 each having a bifurcated rear end straddling its 55 associated sleeve 75 and connected for vertical

swinging movement by a pivot pin 82 to a bracket 83 which extends rearwardly from the sleeve 75. A lever member 84 is also pivoted to each pin 82 and extends forwardly of the sleeve and is pivotally connected at its forward end to a lateral end 85 of a link 86. Each link 86 extends upwardly and is pivoted at its upper end to the sleeve 77 disposed thereabove. Each lever 84 carries a latch 88 operating over a toothed sector 89 fixed to the sleeve 75. The levers 84 with their latches 88 released may be swung downwardly at their outer forward ends and in so moving will fulcrum on the link portions 86 to swing the ends pivoted at 82 thereof upwardly for elevating the frame 10, 11 relatively to the wheels 70 and 71, aided by the spring 76.

The beam structure 30 is latched against rotation and in substantially a horizontal plane by a latch 90 which engages under one of the beam ends 34 or 35. The latch 90, as best illustrated in Figures 3 and 4 is pivoted at 91 to a bracket 92 which is secured to a cross brace 13 extending between the frame parts 10 and 11. Latch 90 has a forward projection 94 pivoted to one end of a link 95 by a pin 96. The other end of link 95 is pivoted on the laterally bent end 97 of a rod 98 which is likewise pivoted to the forward end of a U-shaped member 99, the rearwardly extending legs of which straddle the latch 90 and the lower end of bracket 92 and are pivoted to the latter by a pivot pin 103 which extends loosely through a slot 102 in the latch 90 whereby said latch can swing relatively to the member 99. One end of a spring 103 is connected to the rod end 97 and the other, rear end of said spring is connected to a pin 104 carried by the ears 105 of the bracket 92. A latch 106 is pivoted on pin 104 and is urged to a position to engage over either the beam end 34 or the beam end 35 by a spring 106a. The laterally bent upper end 107 of the trip rod 98 operates in the slot 108 which extends longitudinally of a trip lever 109. Whereas in Patent 1,915,866, said slot 108 must be of a predetermined length, the slot 108 of the present invention may be of any desired length as said slot is not intended to limit the movement of the end 107 when the lever 109 is swung forwardly, as will hereinafter become apparent. A rope or cable 110 is connected to the upper end of the lever 109 and extends forward to a position where it can be grasped by the operator of a tractor 17 to which the plow is coupled. The lever 109 is normally retained in its rear full line position of Figures 3 and 4 by the spring 103. When thus disposed, the beam structure 30 is latched against rotation relatively to the frame 10, 11.

Each bracket 74 is provided with an extension 120 on which is pivoted a latch lever 121, near but spaced from the rear end of said latch lever. A spring 122 urges each latch 121 to swing clockwise and such movement is limited by the forward end of each latch engaging a crank 123 on the end of a crank shaft 124, said shaft having a crank at each end thereof and having the trip lever 109 fixed to an intermediate portion of said shaft.

A latch 130 is pivoted on each bracket extension 120, said latches 130 being urged to swing counterclockwise as seen in Figures 3 and 4 by the springs 122 and being limited in counterclockwise swinging movement by engagement with the toothed sectors 89. Each latch 130 has a hook 131 facing downwardly and rearwardly adapted to engage a link end 85. The latches 130 are alternately disabled from engaging a link

end 85 by a tripping ring 132 which engages the crank end 133 which is formed integral with the latch 130 and disposed below the pivot thereof. Each beam end 34 and 35 carries a tripping ring 132, which tripping rings are disposed adjacent the opposite ends of said beam ends so that the latches 130 are thus alternately disabled.

The parts previously described are disclosed in Patent 1,915,866 and the operation of these parts has therefore not been described in detail. Further, other less essential parts of the present invention corresponding to those of the prior patent have not been described. However, certain of the parts previously described are modified to a certain extent for accomplishing the novel automatic results of the present invention to render the plow automatic in operation and substantially foolproof. In furtherance of this end, the side frame members 10 and 11 near their forward ends are provided with transversely aligned bearing hangers 170 in which a transverse shaft 171 is journaled. A lever 172 is fixed to the shaft 171 adjacent each end thereof. The levers 172 extend rearwardly from the shaft 171 and are each provided with a longitudinally elongated slot 173 adjacent its rear, free end. Each of the latch levers 121 is provided with a forwardly projecting extension 174 having a downturned forward free end to which one end of a link 175 is pivotally connected by a pivot pin 176. The two links 175 extend downwardly from the latch extensions 174 and are slidably and pivotally connected at their lower, free ends each by a pivot pin 177 to the rear end of the lever 172, disposed therebeneath. The pivot pins 177 slidably and turnably engage in the slots 173. A contractile coiled spring 178 is secured at its lower end at 179 to each latch lever 121, forwardly of the latch lever pivots and said springs 178 extend upwardly and rearwardly and are secured at their opposite ends at 180, each to the link 86 which is disposed substantially in alignment therewith. The springs 178 are connected to the links 86 adjacent the upper ends of said links but could be equally well connected to the sleeves 77.

Referring to Figures 3 and 5, an arm 181 is journaled on the crank shaft 124 on one side of the trip lever 109 and projects upwardly therefrom and rearwardly with respect to said trip lever and has a laterally projecting free end 182 which extends in a direction away from the trip lever 109. The arm 181 is provided intermediate of its ends with a laterally projecting pin 183 which extends in the same direction as its end 182 and which loosely engages an elongated longitudinally disposed slot 184 in one end of a connecting rod or link 185. The link 185 extends downwardly and forwardly from the pin 183 and is pivotally connected at 186 at its lower, forward end to the free end of a lever 187. The lever 187 is fixed to and projects rearwardly from the shaft 171, intermediate of the ends of the latter. A contractile spring 188 is anchored at one end to the extension 182 and extends downwardly and forwardly therefrom and is anchored at its opposite end to the connecting rod 185, forwardly of its slot 184 and functions to support the arm 181 in its position to Figures 3 and 5. The spring 188 additionally functions to retain the slotted rod portion 184 in engagement with the pin 183.

One leg of a substantially U-shaped bracket 189 is secured to the rear edge of the trip lever 109 for supporting the bracket behind and in

laterally offset relationship to the trip lever. An elongated slot closing slug 190 is pivotally connected near its upper end by a pin 191 to the bracket 189 and is supported by said bracket in laterally offset relationship to the trip lever 109 to swing across one side thereof. A guide 192 is fixed to and projects from the back edge of the trip lever 109, below the bracket 189 and has a hook portion at its rear end engaging around the back edge of the lower portion of the slug 190. Said member 192 functions with the bracket 189 for guiding the swinging movement of the slug 190 in a plane substantially parallel to the plane of the lever 109 and in laterally offset relationship thereto. The guide 192 additionally functions as a stop for limiting the swinging movement of the slug 190 rearwardly of the lever 109 in a clockwise direction on its pivot 191. A spring 193 is anchored at one end to the lever 109 and is connected at its opposite end to the upper terminal of the slug 190, above its pivot 191 to urge said slug to swing in a clockwise direction for displacing the lower portion of the slug away from and rearwardly with respect to the slot 108. The slug 190 is provided with an extension arm 194 which extends downwardly from its bottom edge and adjacent its back edge and which has a laterally projecting free end portion 195 which extends across the arm 181 and is disposed in front of said arm, as clearly illustrated in Figures 3 and 5.

Referring to the operation of the plow as described in Patent 1,915,866, after the plow beam has been tumbled in order to release the latch members 121 from engagement with the link ends 85 to allow the members 84 to swing upwardly to engage either one of the hooks 131 or the lever 80, the trip lever 109 is swung forwardly slightly by a pull on the rope 110 to swing the cranks 123 upwardly to rock the latches 121 counterclockwise to their released, dotted line positions of applicants' Figure 3. The slot 108 of the patented structure permits this operation to occur without a downward thrust being exerted on the link 98. However, it will be readily apparent that should the rope 110 be pulled too forcibly its latch 90 would also be released to allow the plow beam to tumble. However, with applicants' structure the slot 108 may be made sufficiently long so that regardless of how far the trip lever 109 is swung forwardly the links 98 will not be displaced downwardly and consequently the latch 90 cannot be released, so long as the slug 190 is in its retracted position of Figures 3 and 5, which position it will always assume when the plow is in a transport position, as illustrated in Figure 3, for a reason which will hereinafter be described. Accordingly, after the beam structure has been released and tumbled a forward pull is exerted on the rope 110 to swing the trip lever 109 forwardly to elevate the cranks 123 thereby rocking the latch levers 121 counterclockwise to disengage them from the link ends 85 to allow the members 84 to swing upwardly. The members 84 will be engaged, one by one of the latch hooks 130 and the other by one of the levers 80, after being released by the latch levers 121, in the same manner that said members 84 and link ends 85 are caught in the operation of the plow of Patent 1,915,866. However, when this occurs the frame 10, 11 will move downwardly relatively to the wheels and axles and with respect to the sleeve 77 and links 86 and the springs 178 which have been slacked

while the frame is in its raised position of Figure 3 are thereby tensioned by a downward movement of the frame so that said springs exert an upward pull on the latch levers 121 forwardly of their pivots and thus function to retain the latch levers in their inoperative positions as seen in dotted lines in Figure 3 and in full lines in Figure 4, in which positions the rear ends of the latch levers 121 are incapable of engaging and latching the link ends 85 in their positions of Figure 3. This is of particular importance since ordinarily the transport latches 121 are rocked to their released positions before the plow reaches the end of a furrow into which one of the wheels is dropped, after making a turn at the end of a field, in order that the plow elements may assume sub-soil positions at the end of the field. Consequently, the wheel which is in a lowermost position relatively to the frame and which is to travel in the furrow will drop into the furrow. When this occurs or when the wheel strikes a hole in the furrow the wheel will drop downwardly relatively to the frame, assisted by the spring 16 connected to the axle of said wheel and if care is not exercised the associated member 84 and the link end 85 will swing downwardly and be relatched by the transport latch 121 in the position of Figure 3 and while the other wheel is in a fully raised position so that the plow element nearest the wheel will be completely out of the ground and neither plow element will operate at the desired depth. In the plow of the prior patent the transport latches 121 immediately return to positions to relatch the link ends 85 after being rocked by the cranks 123 to released positions. However, with the present structure the tension on the springs 178 maintain the transport latches 121 in their released positions of Figure 4 and thereby effectively prevent this inadvertent relatching of one side of the frame in a transport position.

Likewise, the springs 178 in rocking the transport levers 121 to their positions of Figure 4 exert an upward pull on the links 175 either of which is capable of swinging its associated lever 172 upwardly to turn the shaft 171 clockwise from its position of Figure 3 to its position of Figure 4. When this occurs, the lever arm 187 is swung upwardly and forwardly to its position of Figure 4 and in so moving exerts a forward pull on the connecting rod 185 to move it from its position of Figures 3 and 5 to its position of Figure 4. When this occurs, after the connecting rod is moved relatively to the arm 181 as provided for by the slot 184, the rear end of said slot will engage the pin 183 to swing the arm 181 in a clockwise direction relatively to the shaft 174 on which it is journaled from its position of Figures 3 and 5 to its position of Figure 4. In so moving, the arm 181 will strike the extension 195 to displace it forwardly and thereby swing the slug 190 counterclockwise on its pivot 191 from its position Figures 3 and 5 to its position of Figure 4. In this latter position, the bottom edge of the slug 190 extends across one side of the slot 108 above the link end 107, which is disposed in the lower end of said slot and thus provides a slot closure to prevent the link end 107 from sliding upwardly relatively to the slot 108. It will thus be readily apparent that when the plow 9 has reached the end of the field the latch 90 can be readily released by a pull on the rope 110. When this occurs and as soon as the trip lever 109 starts to swing forwardly a downward thrust is exerted on the link 98 for swinging the parts 85

and 99 downwardly so that the link 95 exerts a pull on the latch 90 to swing the latch forwardly to a disengaged position for releasing the beam 39 so that the tumbling thereof can be accomplished, as described in the patented plow structure.

As in the patented plow structure, means is provided in the plow 9 to effect automatic adjustment of the draft line from one side of the center line of the draft vehicle to the other side thereof so that one wheel of the draft vehicle will run in the furrow or for use with plow bodies plowing furrows of different widths. However, with the present plow this shifting of the draft connection each time that the plow is reversed is accomplished automatically rather than by the manual operation of a pull rope, as is required in the patented plow.

As in the patented plow, the forward end of the draft bar 14 is pivotally connected to the tractor hitch plate 16. Likewise, as in the patented plow, the plow 9 is provided with an arcuate cross member 165 to the forward side of which is secured laterally spaced latch keepers 163 and 164. The rear end of the draft bar 14 is provided with a bifurcated portion 196 which engages over and under the arcuate cross bar 165 which guides the rear end of the draft bar in its transverse swinging movement. In lieu of the single latch as provided in the patented structure on the draft bar 14, the plow 9 is provided with a pair of latches 197 and 198 which are pivotally mounted at their lower ends on a pivot pin 199 which is connected to the lower part of the bifurcated portion 196 for swinging movement of the latch members 197 and 198 forwardly and rearwardly of the plow frame from positions in front of the cross member 165. The upper, free end of each latch member 197 and 198 is connected by a contractile spring 200 to the rear end of the upper part of the bifurcated portion 196 so that the latches 197 and 198 are urged rearwardly by the springs 200 toward the cross bar 196 and toward positions for latching engagement with the latch keepers 163 and 164, respectively. A pair of guide sleeves 201 are supported in forwardly converging relationship to one another on the upper end of the pivot 15 by a supporting member 202. The forward end portion of a pair of push rods 203 and 204 are reciprocally mounted in the sleeves 201, said push rods extending rearwardly therefrom in diverging relationship to one another and being pivotally connected at their rear ends by horizontally disposed pivots 204a to the two latch elements 130. Accordingly, when either latch element 130 is swung forwardly by its bottom extension 133 engaging a cam ring 132, the push rod 203 or 204 connected thereto will be displaced forwardly through its guide sleeve 201 and relatively to the other push rod. The push rod 203 is connected by a flexible member 205 to the upper end of the latch lever 197 and the push rod 204 is similarly connected by a second flexible member 205 to the other latch lever 198, said flexible members being secured to apertured ears 206 which depend from the push rods and which are disposed forwardly of the latch levers.

In lieu of the chains 150 and 151 of the patented plow structure, an intermediate link of a chain is secured to one end of a contractile coil spring 207 which is disposed below the draft bar 14. The ends 208 and 209 of said chain extend forwardly from the spring 207 in diverging relationship to one another and are anchored

at their forward ends at 210 to laterally spaced portions of the rear end of the draft vehicle 17. Obviously, separate chains may be utilized between each point 210 and the spring 207 if desired. A strap member 211 is attached at its upper, rear end by a fastening 212 to the under side of the draft bar 14, rearwardly of its pivot 15. The strap member 211 has a downwardly and forwardly offset opposite free end to which one end of a chain 213 is adjustably connected. The chain 213 extends forwardly from the strap 211 and is connected at its opposite end to the rear end of the spring 207. Accordingly, the chain 213 may be adjusted for varying the tension on the spring 207.

Assuming that the latch 198 is engaging the keeper 164, as illustrated in Figures 2 and 3, the draft bar 14 will have its rear end offset to the left so that the axis of the plow will be offset to the left of the axis of the draft vehicle looking from rear to front thereof. The latch 198 is allowed to assume a latching position as the push rod 204 is in a rearmost position whereas the latch 197 is held in a forward, inoperative position as the push rod 203, to which it is connected is displaced forwardly since the cam ring 132 is engaging the extension 133 of the latch hook 130 to which the push rod 203 is connected. As the plow 9 reaches an end of the field and the beam structure 30 thereof is tumbled the draft vehicle 17 executes a figure 8 turn and in the last part of which turn the tractor is turning to the right as seen in Figure 2. The tumbling of the plow structure 30 is completed during the last part of the figure 8 turn and consequently the push rod 203 has been released to move backwardly to release the latch 197 and as the plow structure 30 completes its swinging movement the cam ring 132 connected to the part 35 engages the other member 133 of the left-hand latch 130 to swing the upper portion of said latch forwardly and thereby displace the push rod 204 forwardly. At the time that this occurs the chain 208 will be taut and the chain 209 relatively slack and the spring 207 will be under tension. Accordingly, when the push rod 204 is thus displaced forwardly a forward pull is exerted on the latch 198 thereby through its cable 205 to disengage said latch from the keeper 164. When this occurs the draft bar 14 will be swung counterclockwise as seen in Figure 2 on its pivot 15 sufficiently so that the latch 197 will pass the cam surface of the keeper 163 and will engage behind said keeper to latch the draft bar 14 so that the plow will then be offset to the other side or to the right of the axis of the draft vehicle 17. It will thus be seen that the offsetting of the axis of the plow 9 relatively to the draft vehicle is accomplished automatically when the plow is turned with the draft vehicle at each end of the field whereas in the patented plow the latch must be manually released. In accomplishing the offsetting of the draft bar 14, with the patented plow the rope 166 is pulled to disengage the latch 160 after which the last half of the figure 8 turn must be made short and quick in order to offset the draft bar sufficiently to engage the latch with the other keeper or plate. With the improved offsetting means of the plow 9 not only is the offsetting accomplished automatically but additionally the last half of the figure 8 turn is not required to be made sharp and fast since the tension of the spring 207 will cooperate with either chain end 208 or 209 which is tensioned to provide adequate power to swing the draft bar 14 suffi-

ciently when unlatched from one of the keepers to a position to be latched by the other keeper.

It will thus be seen that a tumble plow of improved construction has been provided wherein manual operation is reduced to a minimum and by relatively simple structural changes the operation of the plow has been rendered substantially automatic in all respects. Further, the plow 9 in addition to having been rendered more nearly fully automatic has also been improved structurally so that it is substantially foolproof and may not be inadvertently released from a proper operating position or inadvertently prevented from assuming a proper operating position including the offsetting of the plow relatively to the axis of the draft vehicle.

Various modifications and changes are contemplated and may obviously be resorted to, without departing from the spirit or scope of the invention as hereinafter defined by the appended claims.

We claim as our invention:

1. A two-way plow comprising a frame having a front end and a rear end, a reversible beam structure rotatably mounted about a horizontal axis on the rear end of the frame, left and right hand plow elements carried by the beam structure and disposed alternately in working positions, a draft bar pivotally mounted on a vertical axis intermediate of its ends on the forward end of the frame, said draft bar being adapted to be connected at its forward end to a draft vehicle, means adjustably latching the other rear end of the draft bar to the frame on either side of the longitudinal axis of the plow in positions for offsetting the axis of the plow to either side of the longitudinal axis of the draft vehicle, said adjustable latching means including a releasable latch structure carried by the draft bar, a latch releasing unit connected to the latch structure and actuated by tumbling of the beam structure to unlatch the draft bar from the frame, and means connecting the draft bar and draft vehicle for swinging the rear end of the draft bar, when unlatched, laterally of the plow and across the longitudinal axis thereof into a position to be automatically latched in an opposite offset position when the draft vehicle and plow are turned to reverse their direction of travel.

2. A plow structure as in claim 1, said latch structure including a pair of latch elements normally disposed in operative positions, said latch releasing unit including individually actuated elements each connected to one of said latch elements and alternately operated by tumbling of the beam structure for alternately moving and retaining the latch elements in retracted, inoperative positions.

3. A plow structure as in claim 1, said means connecting the draft bar and draft vehicle including flexible elements connected to laterally spaced portions of the draft vehicle and extending rearwardly in converging relationship to one another, and a contractile spring forming a connection between the converging ends of said flexible elements and the rear end of said draft bar.

4. A two-way plow comprising a frame, a reversible beam structure rotatably connected to the frame for turning movement in a vertical plane longitudinally of the frame, right and left hand plow elements carried by the beam structure and alternately disposed in working positions, laterally spaced ground wheels supporting the frame and vertically adjustable relatively

thereto, each of said ground wheels having an upright axle portion slidably connected to the frame, linkage means pivotally connected to the upper end of each axle portion and to said frame for adjusting the elevation of the wheels individually relatively to the frame, pivotally mounted latch members releasably engaging said linkage means for supporting the frame in an elevated position relatively to the wheels, manually actuated means for releasing the latch elements from said linkage means, and springs connecting the latch elements to the vertical axle portions for retaining said latch elements in released positions when the frame is displaced downwardly from a fully elevated position relatively to the wheels.

5. A plow structure as in claim 4, and link and lever means forming a connection between said latch elements whereby the tensioning of the spring of either latch element will retain both latch elements inoperative positions.

6. A plow structure as in claim 4, and link and lever means forming a connection between said latch elements whereby the tensioning of the spring of either latch element will retain both latch elements inoperative positions, manually actuated means simultaneously moving said latch elements to released positions, a beam engaging latch, means connecting said beam engaging latch to the manually actuated means for releasing said beam engaging latch by operation of said manually actuated means, said last mentioned means including a link connected to said manually actuated means and normally inoperatively disposed with respect thereto whereby the beam engaging latch is unaffected by operation of the manually actuated means, a linkage unit connected to said link and lever means and operated when the link and lever means is operated by either of said springs for operatively connecting the link to the manually actuated means whereby operation of the manually actuated means will disengage the beam engaging latch to permit tumbling of the beam structure.

7. A plow structure as in claim 4, and link and lever means forming a connection between said latch elements whereby the tensioning of the spring of either latch element will retain both latch elements inoperative positions, a beam latch releasing means including a link inoperatively connected to said manually actuated means, and a member carried by said manually actuated means and operatively connected to the link and lever means for operatively connecting said manually actuated means to the beam latch releasing link when said link and lever means is actuated by the tensioning of either of said springs.

8. A plow structure as in claim 4, and link and lever means forming a connection between said latch elements whereby the tensioning of the spring of either latch element will retain both latch elements inoperative positions, a beam latch releasing means including a link inoperatively connected to said manually actuated means, and a member carried by said manually actuated means and operatively connected to the link and lever means for operatively connecting said manually actuated means to the beam latch releasing link when said link and lever means is actuated by the tensioning of either of said springs.
